N. RUBENSTEIN.

CLOTHES BOILER,

APPLICATION FILED MAR. 28, 1919.

1,341,073.

Patented May 25, 1920.

Inventor:
Nathan Rubenstein,
by James P. Duhamel.

Attorney.

UNITED STATES PATENT OFFICE.

NATHAN RUBENSTEIN, OF NEW YORK, N. Y.

CLOTHES-BOILER.

1,341,073.

Specification of Letters Patent.

Patented May 25, 1920.

Application filed March 28, 1919. Serial No. 285,748.

To all whom it may concern:

Be it known that I, NATHAN RUBENSTEIN, a citizen of the United States, residing at New York, in the county of New York and State of New York, have invented certain new and useful Improvements in Clothes-Boilers, of which the following is a specification.

This invention relates to wash boilers and 10 more especially to clothes strainers to be used in connection therewith and its object is to provide the boiler with a false bottom adapted to be elevated to raise the clothes toward the surface of the water in the boiler 15 so they may be removed without difficulty and certain portable means are provided carrying said bottom and the elevating means which may be readily placed in position or removed, as will be more fully set forth in 20 the following specification, specified in the claims and illustrated in the drawings, wherein:

Figure 1 is a vertical longitudinal sectional view of a wash boiler showing the 25 device applied thereto.

Fig. 2 is a cross sectional view of the same.

Fig. 3 is a plan view of one end of the same.

30 In the use of wash boilers great difficulty has been experienced in placing soiled clothes therein or removing and draining the same on account of the location of the boiler on a hot stove and of the boiling water in the vessel and the difficulty of lifting the washed clothes from the interior of the boiler, especially when there are few clothes in much water.

Various attempts have been made to over- 40 come these difficulties but the inventions have been permanent attachments that make the boiler an expensive device and when slightly worn or leaking will require the discarding of the whole machine.

45 The present invention may be applied to any wash boiler or removed and replaced on another and consists of saddles 5 of a shape conforming with the ends of the boiler 6 and having uprights 7 with bearings 8 at 50 their outer ends.

The lower ends 9 of the uprights are bifurcated and welded or otherwise secured to the inner sides of the saddles 5 while the bearings 8 carry a shaft 10 with a winch 11

at one end and a ratchet wheel 12 near the 55 other end and whose teeth are engaged by the pawl 13. Pins 14 may be provided to enter appropriate holes in the shaft to adjust the distance apart of the saddles so that the device may be arranged for any size 60 boiler and pins 15 are also provided and over which may be hung chains 16 whose ends are secured to loops 17 at the extremities of rods 18 on which are located slats 19 and spacing spools 20, the whole making a 65 frame that is a false bottom and is a strainer and may rest on the bottom of the boiler or be hung a slight distance above the same while the boiling of the clothes is in progress.

If desired, the saddles with the shaft may be removed and set aside so that the depositing of the clothes in the boiler may not interfere with the work and when it is desired to remove them the winch is turned 70 and the chains 16 are wound upon the shaft and the frame slowly moved toward the top of the boiler and above the water. The clothes may now be removed singly therefrom or the whole device lifted off the 80 boiler with the clothes on the frame, or as the pawl 13 engages the teeth of the ratchet wheel 12 it locks the shaft in the desired position and the clothes with the false bottom may be left suspended above the surface of the water to drain until it is found desirable to dry them, or a paddle may be used on them to squeeze the water therefrom.

When the operation is over the saddles 90 may be removed and the whole device stored in the boiler or when any part is injured or broken it may be easily removed and replaced with a new one.

It is obvious that the parts may be otherwise arranged without departing from the essential features above described or from the scope of the appended claims.

What I claim as new is:

1. In clothes boilers, the combination of 100 a boiler, removable reinforcing saddles comprising a semi-circular plate with a flange enveloping the upper edges of the ends of said boiler, a shaft journaled in the saddles, a slatted false bottom in the boiler, chains 105 from the sides of the said bottom and adapted to be wound about the shaft, and a ratchet wheel and pawl for the shaft.

2. In clothes boilers, the combination of a boiler, removable reinforcing saddles comprising a plate and overhanging flange conforming with and fitting over the upper ends and inside of the boiler, extensions above the saddles, a shaft journaled in the extensions and having a crank arm, a false

bottom comprising slats strung on cross rods, chains secured on the ends of the rods and adapted to be wound about the shaft, 10 a ratchet wheel on the shaft, and a pawl on the extension.

In testimony whereof I affix my signature.
NATHAN RUBENSTEIN.
